10 Claims. (Cl. 123—46)

The present invention relates to installations comprising a plurality of auto-generators, producing hot gas under pressure for supplying a receiving machine, more particularly a gas turbine; and it concerns more particularly but not exclusive, among such installations, those in which the auto-generators are free-piston auto-generators.

It should be noted here that by auto-generator is understood a machine comprising, on the one hand, an internal combustion driving part, preferably operating on the two-stroke Deisel cycle, and, on the other hand, a compressor part, the output of which in the form of compressed air is used, at least for its greater part, for supercharging and scavenging the driving part, from the exhaust ports of which issue the hot gas under pressure the production of which is the object of the auto-generator.

The object of the invention is above all to render installations of the kind above specified such that they meet the various requirements of practice better than heretofore.

The invention consists principally in establishing, at least for low loads, a communication between two compressor cylinders of at least two auto-generators for at least a part of each period of their working cycles during which different pressures prevail in these cylinders, such that there is obtained a transfer of air from one of the cylinders to the other and a corresponding reduction of the output of each of them, the magnitude of this transfer being advantageously adjustable either, for a given phase difference, by a variation in the resistance opposed to this transfer by the communication conduit, or, for a fixed resistance of said conduit, by a variation of the phase difference between the auto-generators, or by a simultaneous variation of the resistance of the communication conduit and of the phase difference between the auto-generators.

Preferred embodiments of my invention will be hereinafter described with reference to the accompanying drawings given merely by way of example and in which:

FIG. 1 diagrammatically shows an installation comprising two auto-generators having their outputs connected with a common gas turbine, the injection pump and the means for regulating the delivery of this pump being shown for only one of these auto-generators.

FIG. 2 diagrammatically shows a modification intended to facilitate the starting of the auto-generators of the installation shown by FIG. 1.

FIGS. 3 and 4 diagrammatically show two different positions of the regulating element of the device shown in FIG. 2.

FIG. 5 shows another modification of the installation shown in FIG. 1.

FIG. 6 is a diagram intended for explaining the operation of the modification shown in FIG. 5.

FIG. 7 is yet another modification of the installation shown in FIG. 1.

FIG. 8 serves to illustrate the operation of the modification shown in FIG. 7.

FIGS. 9a, 9b, 9c illustrate the effect of a modification of phase difference between two auto-generators

2

of an installation constructed according to the invention.

The installations shown by the drawings comprise two free-piston auto-generators and a gas turbine fed with power gas from said auto-generators.

Each of these auto-generators A and B comprises, in conventional manner, an internal combustion engine cylinder 1, two compressor cylinders 2, arranged on either side of the cylinder 1, and two stepped pistons 3, each of which comprises an internal combustion engine piston element 3a and a compressor piston element 3b. These two pistons have opposed movements and are connected together by a synchronization device, not shown, piston elements 3a operating as opposed pistons in cylinder 1, of which they control the inlet ports 4 and the exhaust ports, not shown, while the compressor piston elements 3b each operate in their respective cylinder 2, which they divide into an internal chamber 2a and an external chamber 2b. Chamber 2a forms the compressor chamber proper and for this purpose, it is provided on the one hand with suction valves 5, which draw air from a suction casing 6, advantageously common to both of the auto-generators and in communication with the surrounding air, and on the other hand, delivery valves 7, through which the air compressed in chamber 2a is forced, during every inward stroke of pistons 3, into a compressed air casing 8 surrounding the combustion cylinder 1. The respective casings 8 of the two auto-generators A and B can communicate with each other through a conduit 9 or may also be separated from each other, as is indicated diagrammatically, by a closure plate 10 shown in dotted lines.

The external chambers 2b of the two cylinders 2 form return pneumatic power accumulators called "cushions" which, during every outward stroke of pistons 3, store up the energy liberated by the combustion of the fuel in cylinder 1 and converted into kinetic energy during the outward stroke of said pistons, in order subsequently to restore this energy, at least in a large part, to said pistons for ensuring the next inward stroke thereof, during which takes place the compression of the air which, during the preceding stroke, has entered chambers 2a through suction valves 5, as well as the compression of the combustion air which has entered the cylinder 1 through the ports 4.

To ensure stable operation of the auto-generators despite variations in the lengths of stroke of pistons 3 and in the pressures at which air is compressed in chambers 2a and forced into casing 8, the mass of air situated in cushions 2b is regulated by a known device called "stabilizer" 11. This device, provided with non-return valves 11a, 11b and axially movable in a cylinder 12, ensures when moved downwardly the admission of air from casing 8 to cushions 2b through openings 13 and conduit 14, and when it is moved upwardly the outflow of air from the cushions through the same conduit 14 and openings 15. In its middle position, on the contrary (shown in FIG. 1), it interrupts the communication between the cushions and the casing. The movements of this stabilizer are controlled by a stepped piston 16, the various faces of which are subjected to the action, on the one hand, of the pressure prevailing in the casing 8 and supplied by a conduit 17 to the face 16a of piston 16, on the other hand, of the mean pressure prevailing in the cushion and supplied by conduit 18, throttled at 19, to the space under the face 16b of said stepped piston 16, and finally of a pressure taken from the cushion 2b at moments adapted to be controlled from the outside, and supplied through a valve 20, controlled from the outside, and through a conduit 21 to the face 16c of stepped piston 16. Finally, the stabilizer is also under the action of a spring 22, preferably adjustable.

It should be noted that all these details relating to the control of the stabilizer are given by way of example and may be modified in various ways, using for example, in place of the mean pressure acting on the face 16b of stepped piston 16, a pressure taken from the cushion for a predetermined position of piston elements 3b in compressor cylinder 2.

With regard to the injection of fuel into the cylinder 1, this is effected by one or more injectors, not shown, fed by an injection pump 23, the regulating rod 24 whereof is controlled for example by a pressure called "modulated" pressure, which acts on a piston 25 coupled to the rod 24 by means of a cam lever 26, the magnitude of said pressure being determined by the speed governor 27 driven by the turbine 28 of the installation, said turbine being supplied with power gas by auto-generators A and B.

The movements of rod 24 are limited by a stop 29 interposed between the two cam surfaces 30a and 30b of lever 26 and which is controlled by an operating factor of the corresponding auto-generator, for example by the mean pressure in cushions 2b or by an analogous pressure, this pressure being supplied by a conduit 18a to the space under a piston 31 on which stop 29 is mounted.

To ensure the supply of power gas to turbine 28, the exhaust ports (not shown) of combustion cylinders 1, when pistons 3 are in the vicinity of their outer dead points, are placed in communication with a power gas manifold 32 connected to the inlet of turbine 28 by 30 means not shown in detail.

Installations of the kind above described necessitated, at low loads, where the intake pressure of the turbine is reduced, the exhausting of a certain quantity of compressed air or gas produced by the auto-generators, since the minimum output of these auto-generators—which output is determined by the necessity for opening, on every outward stroke of the pistons, the inlet and exhaust ports of the combustion cylinder—is higher than the gas requirement of the turbine. This exhaust of compressed 40 air or gas obviously entails an appreciable loss. Furthermore, it is accompanied by an unpleasant noise. It has already been proposed to reduce this loss by recycling a part of the surplus compressed air to the inlet of the compressor cylinder. This recycling although appreciably reducing the loss of energy, was likewise noisy and necessitated the provision of special suction conduits with sound-absorbing means and heat insulation.

The disadvantages of the known constructions are eliminated, at least in large part, by the main feature of the present invention which consists in providing, at least for low loads, a communication between at least two of the compressor chambers 2a of the two auto-generators A and B for at least part of each period of their working cycle during which different pressures prevail in these cylinders, such that there is a transfer of air from one of the cylinders to the other. Preferably and to obtain conduits of minimum length, this communication is provided between the two compressor cylinders which are situated at the same end of the two auto-generators A and B arranged side by side.

Thus, in the installation shown in FIG. 1, there is provided on the right and left of the two auto-generators A and B a communication conduit 33 connecting the two compressor chambers 2a provided at these ends.

For regulating the magnitude of the transfer from one chamber 2a of each pair to the other, various means may be employed. It is assumed first of all that the two auto-generators A and B are maintained at a constant phase difference of 180° by means to be described hereinafter. In such a case, it is merely necessary to provide, in the communication conduits 33, means which by throttling or more or less complete closure produce in the conduits 33 a variable resistance to the flow of the transferred air. These means effect a greater reduction in the cross-section of conduits 33 as the load of the installation

increases, and close these conduits completely (the resistance to transfer then becomes infinite) when the load becomes at least equal to the value for which turbine 28 can absorb the whole amount of gas supplied by the auto-generators. Once these conduits 33 are fully closed, the installation works in the usual manner solely by regulation of the quantity of fuel injected into the combustion cylinders as a function of the speed of turbine 28.

With regard to the means for controlling the cross-section area of the passage through conduits 33, they may have, for example, the form of slide-valves 34. In the installation shown in FIG. 1, a rod 35 connects together the two slide-valves 34 which control the cross-section areas of the two conduits 33 connecting together 15 the respective cylinders 2 of auto-generators A and B that are located at the same ends of said generators, and these two slide-valves are controlled in response to variations of a factor the magnitude of which depends upon the load under which the installation is operating, the control being such that the cross-section area of the conduits 33 is greater as said load is lower, and that conduits 33 are fully closed as soon as this load exceeds a predetermined value, corresponding to a mean value of the load of the installation. To control slide-valves 34, a rod 35a connects them to a piston 36 subjected to the action of a force the magnitude of which is a function of the load of the installation. For example, this force is exerted by a liquid placed under pressure by a governor 27 driven by turbine 28, said liquid being sent through a conduit 37, on the one hand to piston 36 and, on the other hand, to piston 25 controlling the fuel-regulating rod 24. To reduce the force required to move slide-valves 34 it is advantageous to balance the pressures acting on opposite sides of each slide-valve. For this purpose the end of each slide-valve 34 opposite to that more or less deeply engaged in the corresponding conduit 33 is slidable in a cylinder 34a, and the same pressure is caused to act in this cylinder as that existing in the transfer conduit 33. To obtain this result it suffices to provide a groove 34b in the surface of piston 34, said groove constantly placing cylinder 34a in communication with conduit 33.

Preferably, transfer conduits 33 are situated inside the suction casing 6 of the auto-generators, which considerably reduces the noise resulting from the flow of air through said conduits.

In view of the fact that the cross-section area of the passage through conduits 33, even when the slide-valves are in their maximum opening position, has a limited value, it is not possible to reduce to zero the output of the pair of auto-generators, even when conduits 33 are 50 fully open. Furthermore, such zero output would be by no means desirable in view of the fact that the internal combustion engine portions of the auto-generators always require a certain quantity of scavenging air, but by means of the installation, it is possible to obtain a considerable reduction in the total flow of air at very low pressures. Consequently, an installation according to the invention has a very economical fuel consumption at low load.

When it is desired to increase the output of the auto-generators, the cross-section area of the passage through conduits 33 is gradually reduced. Closing of these conduits is effected for example when the pressure of the power gas at the turbine inlet has a value of from 1.5 to 2 kg. per sq. cm. above atmospheric pressure. For higher pressures, the output of the auto-generators may be adapted automatically to the turbine demand without it being necessary to open conduits 33.

To maintain the two auto-generators forming part of the installation shown in FIG. 1 a phase difference of 180°, any appropriate means may be employed, for example for this purpose a device is used such as that shown in the left-hand part of FIG. 1 and comprising a contactor arm 38, driven at a definite speed for example by means of an electric motor, not shown, and which, in two of its positions at 180° to each other, closes for a short time, by

means of brushes 39 and 40, the circuits 41 and 42 of two coils 43, 44 acting on valves 20 included, for each of the two auto-generators A and B, in the conduit 21 which, when the corresponding valve 20 is open, allows the pressure prevailing at that moment in cushion 2b to act on the face 16c of stepped piston 16. The number of revolutions of contactor arm 38 per unit of time corresponds to the number of oscillations of the opposed free pistons of each of the auto-generators during the same time, and the angular offsetting of brushes 39 and 40, which is 180° in the installation of FIG. 1, determines the phase difference between the cycles of operation of the two auto-generators, as described in detail in my U.S. patent application Ser. No. 777,056, filed November 28, 1958, for "Control Means for Free-Piston or Semi-Piston Engines."

Installations having a plurality of auto-generators as shown in FIG. 1 are generally started with the generators in phase, and it is only after starting that the desired phase difference is produced between the movements of the pistons of the auto-generators. As long as the two auto-generators of the installation shown in FIG. 1 operate without phase difference, after their starting, the compressed air outputs and hence the gas outputs of the auto-generators are unaffected by the position of slide valves 34 so that, at this moment, conduits 33 may be wide open. Consequently, the pressure in the conduits leading to the turbine would rise very rapidly and the auto-generators would stop if steps were not taken to discharge their outputs during this period of running with zero phase difference. To ensure such a discharge as long as the auto-generators are running in phase, according to a particularly advantageous embodiment of the invention, each of the conduits 33 is brought into communication with the surrounding air, or better still with the suction casing, and this communication with the surrounding air or with the suction casing is closed only when the desired phase difference between the auto-generators is obtained.

A particularly simple device for obtaining this result is diagrammatically shown in FIGS. 2 to 4. According to these figures, the communication conduit 33 between two compressor chambers 2a comprises an outlet orifice 45 which, when disengaged, connects conduit 33 directly with the interior of the casing 6. In this case, a hole 46 is provided in slide-valve 34. When this slide-valve is in the position corresponding to the starting of the auto-generators (see FIG. 2), it opens not only conduit 33 but also outlet orifice 45, so that during the starting period, the compressed air in the compressor chambers 2a is recycled through conduit 33 and orifice 45 into the suction casing. At the end of the starting period and after the desired phase difference between the cycles of operation of the auto-generators has been obtained, slide-valve 34 is moved to the position shown in FIG. 3. In this position, the slide-valve closes outlet orifice 45, but still leaves conduit 33 open through the hole 46 provided in said slide-valve. The more slide valve 34 is moved toward the left in FIG. 3, the smaller does the cross-section of passage through conduit 33 become. When the load on the installation has reached the value from which the turbine is capable of receiving all the gases produced by the auto-generators in normal running conditions, that is to say without any recycling or other means capable of reducing the output, slide valve 34 is moved into the position shown in FIG. 4, where this valve completely closes the communication between the compressor chambers 2a of the auto-generators.

In certain cases, the application of the chief feature of the present invention permits a considerable simplification of the entire regulation system of the installation. Such a simplified system is shown in FIGS. 5 and 6, this system being applied to an installation having two auto-generators operating with a phase difference of 180°. It is assumed that the installation has a power which varies only within definite limits, which are above the zone of low powers, for which the turbine could not

absorb all the gases produced by the auto-generators in normal working conditions. In this case, it suffices to open conduit 33 only for starting the installation. Thus, slide-valve 34, which controls conduit 33, can occupy only two positions, one for which it completely closes conduit 33 (position shown in FIG. 5) and the other for which it completely opens conduit 33. For this purpose, there is inserted in the conduit 47, supplying any fluid under pressure to the piston 36 which controls slide-valve 34, a three-way cock 48 which, in one of its positions (that shown in FIG. 5), allows the fluid under pressure to act on piston 36, causing slide-valve 34 to move to its closing position, while, in another position, cock 48 puts conduit 47 into communication with the surrounding air, whereby the spring 49 acting on piston 36 can return the slide-valve to the position for which it fully opens conduit 33.

The operation of an installation such as shown in FIG. 5 is illustrated by the diagram of FIG. 6, where the abscissae are the pressures p of the power gas supplied by the auto-generators, these pressures being proportional to the power which the installation is to deliver, while the ordinates are the outputs D of power gas of said auto-generators. Line I shows the minimum outputs of the auto-generators as a function of the pressures p , while line II shows the maximum outputs of the auto-generators as a function of the pressures, the minimum outputs being those obtained without recycling.

Normally, the installation operates according to curve III between points 1 and 2. It will be seen that for all the points of this curve III, the output D for different pressures p is always between lines I and II, and can therefore be supplied without recycling or other means of reducing the normal output of the auto-generators. Consequently, the installation operates between these points 1 and 2 with slide-valve 34 closed. Only for starting and for idling, when the output capable of being absorbed by the turbine is indicated by the point 0, is slide-valve 34 opened wide, which reduces the power gas supplied by the two auto-generators to the output indicated by the said point 0. After the starting period, conduit 33 is closed by means of slide-valve 34. The pressure and quantity of power gas from the auto-generators then increase very rapidly, until one of the points of curve III between its ends 1 and 2 is reached, said point corresponding to the turbine consumption. Any regulation is effected henceforward normally, solely by variation of the quantity of fuel injected, by means of rod 24, which is controlled by the same means as those already described for the installation of FIG. 1.

It should be noted that, in this installation, intermediate powers between points 0 and 1 cannot be obtained.

It should be noted that in an installation according to FIG. 5, it is sufficient to provide the communication conduit 33 and its slide-valve 34 on one side only of the two auto-generators, that is to say, for example, only between the two compressor chambers at the right-hand ends of the auto-generators. It is true that, during starting and idling, there is produced a slight inequality between the pressures prevailing in the compressor chambers on opposed sides of each auto-generator, but this inequality is necessarily slight, since the air pressure is low in the periods during which it exists. This inequality can be readily supported by the synchronization mechanism which, in each of the two auto-generators, connects the two opposed free pistons together.

Of course, in an auto-generator installation as shown in FIG. 5, it is also advantageous to arrange the communication conduit 33 and its slide-valve 34 inside the suction casing 6 which is preferably common to the two compressor chambers connected together by conduit 33.

Another simplified system of regulation, applicable to the cases where two auto-generators operate with a phase difference of 180°, is shown in FIG. 7 and its mode of operation is illustrated by FIG. 8.

The arrangement of FIG. 7 is applicable to the case

where the auto-generators operate almost always at their maximum power, or to the case where fuel consumption is of secondary importance whereas the simplification of the installation is of primary importance. In the installation shown in FIG. 7, the output of power gas is regulated throughout the entire range of different powers by greater or lesser opening of conduit 33 which connects the two compressor chambers 2a together. Slide-valve 34 completely closes conduit 33 only when maximum power is reached. The slide-valve is controlled by the pressure of a fluid, which pressure varies with the load of the installation, and can be produced by a governor 27 driven by turbine 28.

Regulation of the quantity of fuel injected into the power cylinders of the auto-generators is effected, according to FIG. 7, by an internal control factor of the auto-generators, for example by the pressure in casing 8 of each auto-generator. Thus, according to FIG. 7, lever 26a, which controls the regulating rod 24 of injection pump 23, is actuated by a piston 50 one face of which is under the action of the pressure prevailing in casing 8 and admitted to the piston 50 through a conduit 50a, while the other face is under the action of an opposing spring 51. To give lever 26a and hence rod 24, for every pressure prevailing in casing 8, a definite position, the head 52 of the rod 53 of piston 49 cooperates practically without backlash with a slot 54 provided in lever 26a and having a suitable shape and slope.

The operation of the installation shown in FIG. 7 is illustrated by FIG. 8. In this figure, the abscissae and ordinates as well as curves I and II have the same signification as in FIG. 6. In addition, in FIG. 8, curve IV shows the outputs D of gas necessary for driving the turbine as a function of the pressure p . Finally, curve V indicates the output of the auto-generators as a function of the pressure when the fuel injection is regulated by the device shown in FIG. 7, and comprising more particularly piston 49, the head 52 of its rod 53 and lever 26a with its slot 54, and when no recycling device or communication between the compressor chambers of the auto-generators is provided. Recycling by means of slide-valve 34 in the device of FIG. 7 is controlled in such a manner that, due to it, the actual output of the auto-generators to the turbine is reduced as indicated by the shaded area, so as to conform to the power-gas requirement of the turbine.

In all the installations which have just been described, it has been assumed that the phase difference between the movements of the free pistons of the various auto-generators was fixed and equal to 180° , while the free cross-section of the communication conduit 33 was assumed to be variable, the resistance offered to the transfer of air from one compressor chamber 2a to the other depending upon said cross-section.

According to the present invention, however, the cross-section of communication conduit 33 may be constant, while the phase difference between the two auto-generators may be varied.

For example, by varying this phase difference between 0 and 180° , a variation in output can be obtained such as is illustrated in FIGS. 9a, 9b and 9c, in each of which the diagram of compression in the compressor chamber of one of the auto-generators is designated by A, while the corresponding diagram of the other auto-generator is designated by B.

According to FIG. 9a, it is assumed that the two auto-generators are working in phase, that is to say, the phase difference between them is zero. In this case, the pressure and output of each auto-generator are those of two auto-generators, which have no connection between their compressor chambers. The compressed air pressure and the output are maximum. For a phase difference of 90° (FIG. 9b), the pressure and output are already considerably reduced, and for a phase difference of 180° (FIG. 9c), the pressure and output are very small. In this case in particular, the effective pressures and outputs depend

upon the cross-section of the communication between the connected compressor chambers, because if these cross-sections were infinitely great, and consequently the resistance to transfer is zero, the output of the connected compressor chambers would drop to zero for this phase difference of 180° .

To produce the variation in phase difference between two auto-generators, it is possible to use a device having a rotating arm 38 and brushes 39-40 acting on the opening of valves 20 as shown in FIG. 1. To vary the phase difference between the generators, it is then merely necessary to vary, by a movement of at least one of the brushes 39, 40, the angle having its apex at the centre of rotation of contactor arm 38 and the sides of which pass through brushes 39 and 40. The phase difference between the autogenerators is equal to the value of this angle.

Of course, it would also be possible simultaneously to vary the phase difference between the autogenerators and the cross-section of the conduit or conduits 33 connecting compressor chambers 2a together.

It has repeatedly been stated in the foregoing that it is always advantageous to arrange the communication conduit 33 and its control slide-valve 34 inside the suction casing so as to reduce the otherwise very unpleasant noises which could be produced by the transfer of air under pressure from one compressor chamber to the other. In the various embodiments which have just been described, it has been assumed that one single suction casing is common to the compressor chambers connected together by said communication conduit, and that during the starting period, escape of air is effected into this common casing. This direct escape into the common casing has the great advantage of making a supply pipeline unnecessary. Furthermore, the air thus discharged into the casing during the starting period serves to heat the two generators.

Of course, two separate casings could be provided, one for each compressor chamber. In this case, however, it would be advantageous nevertheless to provide a connection between these two casings.

When the two compressor chambers to be connected together by communication conduit 33 are at some distance from each other, thereby necessitating a certain length for conduit 33, it may be advantageous to replace the single control member 34 by two control members, controlled simultaneously, and each of which is in the immediate vicinity of one of the two compressor chambers, in order thus to reduce the increase in clearance space for each compressor chamber due to the fact that said clearance space includes the portion of conduit 33 extending between said chamber and control member 34.

The communication between the compressor cylinders might be controlled by reciprocating means capable, during every working cycle of the free pistons, of opening and closing the communication between the compressor chambers and adjustable in such manner as to vary the duration of opening of the communication conduit during one cycle. Of course the number of auto-generators having their compressor chambers connected together by a transfer conduit may be greater than two.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

70 What I claim is:

1. An installation which comprises at least two auto-generators, each of said auto-generators including a driving portion consisting of an internal combustion engine, a compressor portion operatively connected with said driving portion so as to be driven by it, said compressor por-

tion including means forming a variable volume chamber, means operatively connected with both of said auto-generators for producing a phase difference between the respective cycles of operation of said auto-generators, and means interposed between said two auto-generators for establishing a permanent direct communication between the respective variable volume chambers of the respective compressor portions of said auto-generators.

2. An installation according to claim 1 which further comprises means for controlling said communication means to vary the resistance offered by said communication means to the transfer of air from one variable volume chamber to the other.

3. An installation according to claim 1 in which said means for producing said phase difference are adjustable so as to permit of varying the value of said phase difference.

4. An installation according to claim 1 in which said two auto-generators have opposed cylinders and free pistons therein, and are disposed in parallel relation to each other, said communication means being provided between at least two compressor cylinders arranged at the adjacent ends of the two auto-generators, respectively.

5. An installation according to claim 1 which further comprises a suction casing surrounding the respective compressor portions of the two auto-generators, said communication means being located in said suction casing.

6. An installation which comprises at least two auto-generators, each of said auto-generators including a driving portion consisting of an internal combustion engine, a compressor portion operatively connected with said driving portion so as to be driven by it, said compressor portion including means forming a variable volume chamber, means operatively connected with both of said auto-generators for producing a phase difference between the respective cycles of operation of said auto-generators,

means interposed between said two auto-generators for placing said variable volume chambers thereof respectively in communication with each other, said communication means being provided with an orifice opening into a space at a pressure at least approximately equal to atmospheric pressure, and valve means for controlling said orifice.

7. An installation according to claim 6 in which said valve means further constitutes means for controlling the cross-section area of flow through said communication means.

8. An installation according to claim 6 in which said valve means is a slide-valve provided with a hole extending therethrough, said slide-valve being capable, in a first position, to open said orifice leading to the surrounding space, in a second position to close this opening but to open, by means of its hole, said communication means between said variable volume cylinders and, in a third position, to close said communication means.

9. An installation according to claim 2 in which said means for controlling said communication means is a control member adapted to occupy only two positions, one for which it fully opens said communication means and the other for which it fully closes said communication means.

10. An installation according to claim 2 further comprising means for regulating the quantity of fuel fed to said auto-generator driving portions in response to variations of the pressure of the gas produced by said auto-generators.
